DESIGN FOR A WATCH DIAL

Abraham Blumstein, Brooklyn, N. Y.

Application July 6, 1935, Serial No. 57,543

Term of patent 3½ years

To all whom it may concern:

Be it known that I, Abraham Blumstein, a citizen of Poland, residing at Brooklyn, in the county of Kings and State of New York, have invented a new, original, and ornamental Design for Watch Dial, of which the following is a specification, reference being had to the accompanying drawing, forming a part thereof.

Fig. 1 is a plan view of a watch dial, showing my new design.

Fig. 2 is a sectional view taken along line 2—2 of Fig. 1.

The characteristic feature of my new design resides in the use of the numerals 3, 6, 9 and 12 instead of all twelve numerals, and in providing indications for the intermediate hours, the indications being provided with baguette precious stones and the numerals being studded with precious stones.

I claim:

The ornamental design for a watch dial, as shown, and described.

ABRAHAM BLUMSTEIN.
